UNITED STATES PATENT OFFICE.

WILLIAM E. GRISHAM, OF TILLAR, ARKANSAS.
COTTON-TIE BUCKLE.

No. 923,042.

Specification of Letters Patent. Patented May 25, 1909.

Application filed August 28, 1908. Serial No. 450,740.

To all whom it may concern:

Be it known that I, WILLIAM E. GRISHAM, a citizen of the United States, residing at Tillar, in the county of Drew and State of Arkansas, have invented a new and useful 5 Cotton-Tie Buckle, of which the following is a specification.

The object of the invention is to provide an article of this character that shall be 10 simple of construction, thoroughly efficient in operation, and in which the assemblage of the band therewith shall be so accomplished as to insure the positive union of the parts under all strains to which they shall be subjected such as those resulting from rough 15 handling of the bale equipped with the fastener, as when the bale is being drayed or transhipped.

With the above and other objects in view, 20 as will appear as the nature of the invention is better understood, the same consists in the novel construction and combination of parts of a bale band fastener, as will be herein-after fully described and claimed.

25 In the accompanying drawings forming a part of this specification, and in which like characters of reference indicate corresponding parts:—Figure 1 is a view in perspective displaying the fastener assembled with the 30 two ends of a bale tie, the latter being broken away. Fig. 2 is a longitudinal sectional view through the fastener, taken on one side of the band. Fig. 3 is a perspective detail view of the fastener, viewed from the inner side. 35 Fig. 4 is an edge view of the fastener.

The fastener shown in detail in Fig. 3, is stamped from a strip of metal of the requisite thickness, is approximately rectangular in shape, and is provided at one end with a 40 transverse band receiving opening 1, and along its two sides with two locking key keepers 2 and 3, which extend from points adjacent to one end of the fastener to points adjacent to the opening 1. The keepers are bent away 45 from the flat body 4 of the buckle plate, by which term the article shown in Fig. 3 will hereafter be designated, to form a salient angle 8, arranged to receive and securely hold the locking key 5, which may be an ordinary wire nail, the head 6 of which will 50 provide a ready means by which the key may be removed by an ordinary pair of pincers.

The term bent as applied to the keepers, is not to be construed as meaning arcuate, as in effect the bends are somewhat angular.

55 As will be noted by reference to Fig. 4, the crests of the bends are not disposed at the central points of the keepers, but are farthest removed from the slotted end of the fastener. This arrangement will cause 60 the inner walls of the keepers from the slotted end of the fastener to the crests of the bends, to be longer, or of less angularity than the remaining lengths of the 65 keepers, resulting thereby in causing the locking key, when strain is applied to the band, to be forced downward upon the ends of the band, and thereby securely hold these parts, as well as the key from loosening or becoming detached.

70 The band 7, which as usual is constructed of a length of sheet iron or other suitable metal, has one end passed through the opening 1, thence bent around the opposite end of the fastener, and disposed upon the top 75 or outer surface of the body 4. The other end of the band is bent in a direction the reverse of the first named end, and is disposed upon the same when the parts are assembled, as shown in Fig. 2. It is designed that the 80 last described bend in the band will be made after the bale has been compressed, although it may be accomplished before this procedure takes place.

85 In the use of the band and fastener, after the bale has been compressed, the band is placed around the bale, and when the free looped end of the band has been disposed between the keepers, as shown in Fig. 1, the locking key is then inserted, and will operate firmly to hold all the parts secured together.

90 The improvements herein defined, while simple in character, will be found thoroughly efficient for the purposes designed and will 95 coact in the production of an efficient and highly durable form of bale band fastener.

I claim:

100 In a device of the class described, a buckle-plate comprising a body portion provided with a pair of longitudinally disposed locking-key keepers, and having a transversely disposed band-receiving opening adjacent to one of its ends; a band having one end

passed through the opening and bent around the other end of the buckel-plate, the other end of the band being bent to form a loop arranged to be disposed between the two keepers; and a key arranged to be inserted between the keepers and the body and through the loop formed in the band.

In testimony that I claim the foregoing as my own, I have hereto affixed my signature in the presence of two witnesses.

W. E. GRISHAM.
